UNITED STATES PATENT OFFICE.

WILLIAM N. THOMAS, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR A COMBINED ESCUTCHEON PLATE AND DOOR-LATCH FRONT.

Application filed March 14, 1928. Serial No. 25,851. Term of patent 14 years.

To all whom it may concern:

Be it known that I, WILLIAM N. THOMAS, a citizen of the United States, residing in New Haven, in the county of New Haven and State of Connecticut, have invented a new, original, and ornamental Design for Combined Escutcheon Plates and Door-Latch Fronts, of which the following is a specification when taken in connection with the accompanying drawing:

Fig. 1 is a front elevational view of a combined escutcheon plate and door latch front embodying my invention;

Fig. 2 is an edge elevation of the same.

I claim:

The ornamental design for a combined escutcheon plate and door latch front substantially as shown.

WILLIAM N. THOMAS.
